UNITED STATES PATENT OFFICE.

WALTER J. REAM, OF SPRING VALLEY, ILLINOIS.

HERNIA BANDAGE FOR INFANTS.

1,404,891.

Specification of Letters Patent. Patented Jan. 31, 1922.

Application filed May 14, 1920. Serial No. 381,359.

To all whom it may concern:

Be it known that I, WALTER J. REAM, a citizen of the United States, and a resident of the city of Spring Valley, in the county of Bureau and State of Illinois, have invented certain new and useful Improvements in a Hernia Bandage for Infants; and I do hereby declare that the following is a full, clear, and exact description of the same, reference being had to the accompanying drawings, and to the numerals of reference marked thereon, which form a part of this specification.

The common umbilical hernia is a source of much annoyance. It is much more common in females than in males, especially in those poorly nourished and rachitic. The tumor is usually one-fourth to one-half inch in diameter; it may, however, be very large, and even become strangulated, when a surgical operation becomes necessary. The ordinary cases, however, require only mechanical treatment. The most important thing is prevention. For this purpose it is necessary, after the cord is separated, to place a firm pad over the navel and to use a snug abdominal band for the first few months.

This invention relates to an improved type of hernia bandage for infants adapted for the prevention or cure of umbilical hernia.

It is an object of the invention to provide a hernia bandage which will not become displaced from its proper position.

It is a further object of the invention to provide a bandage which does not need to be applied so tightly as to restrict the respiration of, or work other damage to the child.

It is also an object of the invention to provide a bandage which can be easily applied and renewed in case it becomes wet or soiled.

Another object of the invention is to provide an adjustable bandage adapted to conform to any size of infant.

Other and further objects of the invention will be apparent from the disclosures in the specification and drawings.

The invention (in a preferred form) is illustrated in the drawings and hereinafter more fully described.

On the drawings:

Figure 1 is a front view of a child wearing the improved bandage.

Figure 2 is an elevation of the bandage itself.

Figure 3 is a section on line 3—3 of Figure 2, showing a slight modification.

Figure 4 is a section on line 4—4 of Figure 2.

As shown on the drawings:

The entire bandage is in one part, consisting essentially of a child's ordinary ribbed undershirt 5, which, as is well known, will stretch or give in a direction transverse to the ribs thereof. This shirt is reinforced in front by knitting integral therewith, sometimes called an overknit, which is so applied that it prevents stretching in the aforesaid direction. Thus there is developed a fabric which will not yield to any substantial degree in its plane.

This reinforced fabric is continued in a tab or strip 9 extending from one side of the shirt and of sufficient length to go around the back of the child and to overlap the front portion as shown at 10 in Figure 1.

The shirt is provided with shoulder straps 7 and tabs 8 which will keep it in position; the tabs 8 being secured by pins 12 to the diapers 13. It is seen that by this means, the bandage is positively prevented from sidewise or upward displacement.

The modification shown in Figure 3 is devised for older children or even adults. The strings or tapes 11 are secured to the tabs 8 and are passed beneath the crotch of the wearer and then tied in place, in lieu of diapers.

It is seen that there is hereby provided a practical bandage for the prevention and cure of umbilical hernia, especially in infants, which is a great improvement over the ordinary bands used, which bands, if applied so that they are not apt to slip, are applied so tightly so that while they answer their purpose fairly well over the umbilicus, they make the character of the respiration of the child entirely thoracic and may produce, or have a tendency to produce, indirect inguinal hernia. In the case of small umbilical herniae after the hernia has been reduced, this improved bandage acts as a truss and will cure a large number of the cases if the hernia is kept reduced and the band in place for a sufficient length of time.

The ordinary band when used, first, slips around the body, also up from the abdomen over the chest, and it rolls up from below. The ordinary band is made of a material that will give, that is, stretch in one or more

directions, and thus is worthless as protection against hernia.

In the use of this band, the double thickness of knit in this garment takes the place 5 as regards warmth of the band and the binder. During the first three weeks, this band may be applied over the ordinary belly band in order to prevent it from slipping and reinforce it, also the belly band does 10 not have to be applied so tightly. After the first three weeks, when the belly band is removed, it has been found to be absolute protection against umbilical hernia from any of the above mentioned causes.

15 I am aware that many changes may be made, and numerous details of construction may be varied through a wide range without departing from the principles of this invention, and I therefore do not purpose limiting the patent granted hereon, 20 otherwise than necessitated by the prior art.

I claim as my invention:

A knitted ribbed undershirt, an overknit

reinforcement integral with the front of the shirt and extending from the lower edge 25 thereof to above the wearer's umbilicus, the ribs of the reinforcement being at an angle to the ribs of the rest of the shirt, whereby stretching of the reinforced portion is prevented, a strip, continuous with the reinforcement but of lesser width, extending from one edge of the reinforcement and of sufficient length to go around the back of 30 the wearer and be fastened to the reinforced front of the shirt, and means extending from 35 the lower edges of the garment both in front and behind by which the garment may be secured against upward movement.

In testimony whereof I have hereunto subscribed my name in the presence of two 40 subscribing witnesses.

WALTER J. REAM.
